UNITED STATES PATENT OFFICE.

CLIO K. WILSON, OF AURORA, ILLINOIS.

DESIGN FOR A DRESS, APRON, OR LIKE GARMENT.

57,293.

Specification for Design.

Patented Mar. 8, 1921.

Application filed July 16, 1920. Serial No. 396,842. Term of patent 14 years.

To all whom it may concern:

Be it known that I, CLIO K. WILSON, a citizen of the United States, residing at Aurora, in the county of Kane and State of Illinois, have invented a new, original, and ornamental Design for Dress, Apron, or like Garment, of which the following is a specification, reference being had to the accompanying drawing, forming a part thereof.

I claim:

The ornamental design for a dress, apron or like garment as shown.

CLIO K. WILSON.
